TELEGRAPH SWITCHING SYSTEM

Arthur J. Doré, Chicago, Ill., assignor to Teletype Corporation, Chicago, Ill., a corporation of Delaware

Application March 3, 1943, Serial No. 477,799

7 Claims. (Cl. 178—3)

The present invention relates to communication switching systems and apparatus and more particularly to systems for selectively communicating telegraphically with a plurality of telegraph stations. Specifically, the invention relates to a system wherein one or more of a plurality of telegraph signal retransmitting devices may be rendered responsive to incoming message signals originating from among a plurality of loop circuit transmitters or broadcast stations individually identifiable according to a system of call letters.

Under certain conditions of telegraphic communication a plurality of outlying telegraph stations are connected together over a common loop circuit and are operated for relaying information successively or in accordance with any other plan to a common central station whereat there is prepared for retransmission, perforated tape bearing the messages broadcast by certain ones only of said stations to the exclusion of the information transmitted from other ones thereof.

In accordance with a specific contemplation the election to record upon a tape from among said several broadcast stations or in other words, the determination as to which one or ones of the stations is to affect the operation of predetermined perforators is preferably made at the central station by predeterminedly associating reperforator shunt relays to the control of corresponding ones of a series of reperforator selecting relays. This arrangement of establishing connections between certain broadcast stations and certain transmitting reperforators may be in accordance with a permanent arrangement or as where preferable, the association may be varied or adjusted throughout the course of a given period of transmission so that, for example, at certain hours of a day broadcast transmitting stations which disseminate certain information may be associated with reperforators which require such information then only and not at other hours of the day.

The present application is related to an application filed concurrently under the name of W. J. Zenner, Serial No. 477,800, filed March 3, 1943, which includes a telegraph switching system also designed for automatically establishing communication between outlying stations and predetermined ones of a series of retransmission perforators but which connections will prevail for a limited period of time only; that is, coincident with the transmission of message matter not exceeding one page width in length. Messages which exceed one line in length can be trans-

mitted by the system shown in said copending application, only by sending a new circuit establishing signal at each line beginning and thereby reestablishing the circuit association at the commencement of each line. In some instances such a system might be operated at some economical disadvantage and in order to overcome this difficulty it is herewith proposed to provide a system having a generally similar objective but providing for the continuous circuit establishment between broadcast transmitting and reperforating station apparatus during the communication of message material which exceeds one line in length without requiring reestablishment of circuit connections at the start of each line of printing.

Accordingly, the primary object of the present invention is the provision in a system of station selection by means of which retransmission apparatus may be variously conditioned for operation according to station identification signals that are transmitted along with line-length or bulletin messages and where such apparatus once conditioned may, under the control of preventative signals, be continued in condition for a duration exceeding a single line length of communication.

Briefly stated, the present invention contemplates a system of communication control whereby a series of outlying stations is connected over a single incoming line with a common impulse repeating relay located at a central office. The common relay repeats the signals transmitted by any one of the outlying stations to a series of local relays serially connected in a loop circuit, one of which may be associated directly with a receiving page printer thus making a page recording of all of the message material received over the line. Another one of the relays may be associated with a mechanical code selecting apparatus in which a plurality of special function selector bars are provided for closing supervisory contacts which will be described later and which affect the performance of a set of conditioning relays. In addition to these, a series of reperforator control relays are provided in the loop circuit, each one of which affects the initiation and control over a tape reperforator such as of the type disclosed in U. S. Patent No. 1,884,743. Of these latter relays all are provided with electrically shuntable armatures so that any one or more of them may be rendered ineffective in the performance of initiating its associated reperforator apparatus through the simple expedient of maintaining closed its control circuit notwith-

standing the fluctuations of its armature in response to the signals induced upon it by the central station loop circuit. The manner in which these shunt circuits are supervised will be described in greater detail hereinafter. The aforementioned mechanical selector apparatus has for its primary purpose the supervision over a system of conditioning relays which in turn affect the performance of a series of shunt selector relays in the supervision of said shunt circuits.

For a more comprehensive understanding of the present invention, reference will now be had to the accompanying drawings and to the following detailed specification in which corresponding reference characters designate similar parts throughout and in which,

Fig. 1 is a schematic circuit diagram of a central station illustrating in block outline the various pieces of apparatus utilized in the performance of the afore-designated objects;

Fig. 2 is a portion of a schematic circuit diagram featuring a set of conditioning relays and a conventional designation of a mechanical selector associated therewith which perform a primary supervision over a series of shunt selector relays illustrated in another portion of the schematic circuit diagram;

Fig. 3 is a further portion of the schematic circuit diagram described in connection with Fig. 2 featuring the electrical circuit arrangements of the shunt selecting relays; and

Fig. 4 is a further portion of the schematic circuit described in connection with Figs. 2 and 3 featuring a set of reperforator shunt relays whose armatures control the establishment of corresponding shunt circuits for affecting the performance of the reperforators.

In Fig. 1 of the accompanying drawings, the reference character 11 designates a dotted outline representing a central station. A signaling line 12 extending into this office is connected with a polar relay 13 whose armature 14 responds to the impulses induced over line 12 by any one of a series of outlying stations 15, 16, or 17. When no signals are impressed upon the incoming line 12, armature 14 is adapted to engage its left contact 18, maintaining closed a loop circuit 19, which includes in series the receiving relays 21 and 22 of monitoring page printer 41 and a mechanical selector unit 42, both of which will be described later, as well as four control relays designated 23, 24, 25, and 26, which supervise the performance of four reperforators 27, 28, 29, and 31.

Each of the prepared tapes or control forms which leaves its reperforator 27 to 31 is thereafter fed through a sensing apparatus of a retransmitter 32, 33, 34, or 35. Accordingly, the signals which are impressed upon the respective prepared control forms are by the associated tape transmitters converted into electrical signal impulses sent out over lines 36, 37, 38, or 39.

The subscriber's receiving stations which may be located variously upon the lines 36 to 39, may be interested in obtaining information disseminated by different ones of the afore-mentioned series of broadcast or transmitting stations 15, 16, 17, etc. Moreover, the subscribers on a line may desire to exclude information sent by others of the broadcast stations. Accordingly, means have been provided whereby under the control of adjustable switching apparatus, any one or more of the reperforators 27 to 31 may be made responsive to the information broadcast by any of the transmitting stations 15, 16, 17, etc. to the

exclusion of such information broadcast by other ones of said stations. The manner in which this selectivity is accomplished will now be described in specific detail having particular reference to the disclosures of Figs. 2 to 4, inclusive, the apparatus thereof being but generally designated by symbols in the schematic showing of Fig. 1.

The magnet 21 controls the operation of a monitor printer 41, and since this magnet is located in the primary loop circuit and is accordingly responsive to all of the signal impulses coming in over line 12, the matter printed by the monitor printer 41 will include the total of all broadcast messages over line 12 coming from any one of the broadcast stations 15, 16, 17, etc. The reference numeral 42 designates a mechanical selector apparatus which may be of the type illustrated in copending U. S. application Serial No. 405,301 filed August 4, 1941, now Patent No. 2,323,438, granted July 6, 1943. This mechanism is provided with a number of pull bars which are responsive to various code combinations of signaling impulses.

In regard to the manner in which selector 42 exercises the supervision over the apparatus which comprises the instant system, the disclosure is concerned with but five pull bar selection operations which preferably do not in an ordinary page printer apparatus affect any printing operation but only certain collateral functions such as space, blank, letters shift, line feed, and carriage return. These signals have been chosen rather than printing signals in order that no printing operation will be made by the monitor printer or any other printers which may be connected into the line, during the time that the station selection functions are performed.

It is proposed that each of the broadcast stations 15, 16, 17, etc. be apportioned a period of time in a succession of periods one for each station broadcasting over line 12, during which it will transmit one or more messages concerning items of information which are to be issued to any or all of the outgoing lines 36, 37, 38, or 39. Each such broadcast station 15, 16, 17, etc. will begin its interval of transmission by sending out a letters shift signal, which will serve to close the contact pair 55 and then issuing a carriage return signal. In the operation of a page type printer such as represented by the reference character 41, Fig. 1, this type of signal serves to return the printing carriage to the beginning of a line in preparation for the printing of a message at the start of such line. Thereafter the broadcast station follows with an identification signal or combination of such signals made up preferably of the three special function signals, letters shift, space, and blank. Following this the station will transmit another carriage return signal designating that its identification signal has been completed and that the message proper is to be sent. In order to make certain that sufficient time has been permitted to elapse following the second carriage return signal and preceding the first message character to clear said carriage return signal through the selector mechanism 42 and the conditioning and shunt selector relay groups as will later be explained, a precautionary time delay signal in the form of another letters shift code is transmitted. This case signal will have no effect whatever at this time on either the page printer or the line selecting apparatus. Thereafter the station will proceed to transmit its message which may consist of any number of words constituting a page

width line or, in accordance with the instant adaptation, even exceeding such a line in length.

When a message is completed before the printer reaches the end of a line or at the end of a line the carriage should be advanced to a succeeding line and the transmitting station will accordingly issue a line feed signal. Under ordinary conditions of operation, the line feed signal when followed by a carriage return signal performs a restorative operation and thereby places the apparatus in readiness for establishing a new connection and for receiving a new message. Means have been provided, however, whereby upon the issuance of a line feed signal which is followed by a special signal before the carriage return signal, there is prevented the disconnection then in existence and instead the printing of a succeeding line may continue as a part of the same line connection and without requiring that a new selecting signal be transmitted.

The selection for retransmission among the several reperforators 27 to 31 is obtained by a set of nine shunt selecting relays generally designated at 43, Fig. 1, and diagrammatically illustrated in Fig. 3 of the complete circuit diagram. In accordance with the operation of these nine relays any one of which may be energized to the exclusion of the remainder, certain of the four reperforators 27, 28, 29, and 31 are placed in condition to respond to the signal impulses repeated by their respective magnets 23 to 26, inclusive. The manner in which these shunt selecting relays are energized will now be described in conjunction with an explanation of the three conditioning relays which constitute a set generally designated 44, Fig. 1, the wiring diagram of which is disclosed in the right-hand portion of Fig. 2 and the individual relays of which are designated 45, 46, and 47. The mechanical selector 42 is portrayed conventionally in Fig. 2 by its five selectable elements which have been indicated as follows:

The carriage return code bar by the index CR, the letters shift code bar by the index LS, the space code bar by the letters SP, the blank code bar by the letters BL, and the line feed code bar by the letters LF. Upon the energization of any of the code bars CR, LS, SP, or BL, there is effected the closure of an associated contact pair 48, 49, 51, or 52. Another contact pair designated 53, however, which is operated by the selectable bar LF, remains normally closed and is opened briefly during the selective operation of the line feed bar LF.

A mechanical selector apparatus 42 of the type contemplated may consist of a modified telegraph printer provided with a contact pair 54 that is operated by the universal bar and thereby closed invariably with the receipt of each signal, and a contact pair 55 which is closed during the time that the case shift mechanism is disposed in its letters shift position, and open during the time that it is disposed in its numerals shift position.

The reference character 56 designates a circuit connecting in series the contact pairs 54 and 55 with the carriage return and line feed contact pairs 48 and 53. In order to be effective towards the purpose of station selection the mechanical selector apparatus will of necessity be required to be placed in the letters shift position, as already explained. When this apparatus is disposed in its figures shift position, the contact pair 55 will remain open, and the completion of supervisory control will thereby be prevented.

There will now be described illustrative examples of operation to show how the conditioning relays 45, 46, and 47 in response to the various manners of operation of the mechanical selector bars CR, LS, SP, BL, and LF, serve to energize one of the shunt selecting relays constituting the group designated SP, SP—LS, SP—BL, BL, BL—SP, BL—LS, LS, LS—BL, and LS—SP.

Let it be supposed that outlying stations on trunk lines 36 and 38, Fig. 1, are desirous of receiving information transmitted over the line 12 by the broadcast station 15. Any reperforator shunt relay of the Fig. 3 group may be employed for cutting out those reperforators 28 and 31 which are not then to receive signals, by accordingly conditioning the shunt relays 57, 58, 59, and 61. These relays form part of a unit generally indicated 62, Fig. 1, and they in turn may upon energization attract their associated armatures 63, 64, 65, and 66, respectively, interrupting obvious shunt circuits that normally parallel a corresponding series of contact armatures 67, 68, 69, and 71, which fluctuate in response to the energization and de-energization of the loop circuit supervisory magnets 23 to 26, afore-described, as controlling the reperforator units 27 to 31, inclusive.

Under the example chosen the lines 36 and 38 are to receive signals transmitted by station 15. Accordingly, it will be required that shunt armatures 64 and 66 become attracted by the energization of their associated shunt relays 58 and 61, so that thereafter when the armatures 67 and 69 fluctuate in response to the energization of magnets 23 and 25, the opening and closing of the control circuits of reperforators 27 and 29 will be effective toward the purpose of operating the tape perforating and code conditioning apparatus of such units, while the other units 28 and 30 remain dormant.

Referring now more particularly to Figs. 3 and 4, it will be noted that in order to energize magnets 58 and 61 it will be necessary to place current upon the bus bars 74 and 75 while excluding it from the bus bars 72 and 73. For this purpose any one of the shunt selector relays SP, BL, LS—SP, etc. may be especially conditioned, for it is but necessary that such relay have its objective armatures 76 to 79 electrically strapped to cable 82 in a suitable manner. Thus, to render relay SP—BL effective in the performance of the instant selection, its objective armatures 77 and 79 must be connected to cable 82 while its armatures 76 and 78 are disconnected therefrom.

In accordance with a contemplated design, each one of the shunt selecting relays SP, SP—LS, etc., is provided with four contactors 76, 77, 78, and 79, communicating respectively with the bus bar contacts of conductors 72, 75, 73, and 74. To assign any one of the shunt selecting relays to the preparation of any combination of the lines 36 to 39, it is but necessary to connect the enabling contact switches 81 thereof which prepare a ground supply circuit from the common bus wire 82 upon the armatures 76 to 79 so that thereafter, upon energization, this ground will be supplied to the corresponding shunt relay energizing bus 72 to 75.

For convenience in manipulating the ground conditioning contactors 81, it is proposed that a multiple button panel type of control switch 830, Fig. 1, be provided having thereon suitably indexed push button devices for effecting the closure of those contactors 81 of any relay SP, SP—LS, SP—DL, etc. which is to become associ-

ated with predetermined ones of the outgoing lines 36 to 39. In this way subscribers' stations by having previous arrangements with the control operator at the central station may obtain limited service from certain ones of the broadcast stations 15, 16, 17, etc., by having line connection with such stations at predetermined intervals of a day to the exclusion of such connection at other times.

Under the example chosen, a particular broadcasting station 15, having the identification symbols of space-blank signals, will be operated to retransmit signals over the outgoing lines 36 and 38. This will require that a relay such as the one designated SP-BL, be selected and have its objective armatures 71 and 79 connected so as to prepare for ground which is later supplied over the bus wire 82 to the lines 74 and 75. It is equally important that its armatures 76 and 78 be disconnected from ground. Upon the energization of relay SP-BL, by the space-blank selecting signal combination, its armatures will be locked to operated position and will connect with bus wire 82 which later obtains ground to enable the energization of the shunt relays 58 and 61. There will now be explained the manner in which these selecting signals are effective in energizing relay SP-BL.

Any station identification signal transmission will be preceded by a carriage return signal, the receipt of which by the mechanical selector 42, Fig. 2, will cause its associated carriage return code bar CR to be moved into its selected position closing the contact pair 48. It will be recalled that the selector is placed into its letters shift position so that the contact pair 55 is closed and as an incident to all operations the universal contact pair 54 is momentarily closed thereby completing a circuit which is traceable from positive current source at 83, over lines 84 and 85, through the winding of the third conditioning relay 47, then out over conductor 86, contact pair 88-87 (normally in engagement), line 89, through the contact pair 48 (now closed), contact pairs 54 and 55 of conductor 56, through the contact pair 53, to the negative bus wire 91.

As a result of the completion of the aforementioned circuit, conditioning relay 47 becomes energized drawing up its contact tongues 92, 93, 94, and 95. As a result of the operation of contact tongue 93, a holding circuit is prepared for relay 47 traceable from positive terminal 83 over lines 84 and 85, through the winding of relay 47, line 96, contact pair 93 which is now closed, line 97, contactor 98 of relay 45 which is engaged during the de-energized condition of said relay, line 99, to the contact point 101 which is now engaged with the make-before-break contactor 102 during the de-energized condition of relay 46, through the winding of said relay 46, out over line 103, contact pair 104 which remains closed until relay 46 is operated, line 105, contactor 106 which remains closed during the de-energized condition of relay 45, lines 107, 175, and 108 to the junction point 109. Thereafter, this circuit is traceable over line 111 to the contact pair including contactor 95 which is at this time closed due to the energization of relay 47, to grounded negative bus terminal 91.

As a result of this circuit relay 46 becomes energized drawing up its armatures 112, 104, 113, 114, 115, 87, and 116.

As a consequence of the attraction of its armature 112 against the make-before-break contactor

102, a locking circuit is established for relay 46 traceable from positive bus wire 83, line 84, conductor 117, armature 112 which is now in engagement with contactor 102, winding of relay 46, then out over line 103, contact pair 114 which is now closed to the energization of relay 46, then over line 118, contact pair 95 to negative bus terminal 91.

It is to be noted that ground is also available 10 to the afore-described conductor 118 over line 111, contact pair 53 to grounded bus 91 and this latter course is effective when contact pairs 101-102 become separated due to the energization 15 of relay 46 thereat opening the holding circuit for relay 47 and causing the opening of contact pair 95 which is the alternative ground connection for conductor 118.

The third conditioning relay 47 is thus released 20 and all of its armatures are restored and now only relay 46 remains energized with its several armatures drawn up into their forward position. As a result of the closure of contact armature 116 25 with its contact point, minus current from the negative bus bar 91 is made available to the contact pairs 49-51 and 52 of the letters shift, space, and blank selector bars of the mechanical selector 42. This circuit is traceable from minus bus bar 91 through the normally closed contact pair 53 then through the contact pairs 55 and 54 of branch conductor 56, line 119, contact pair 116, and line 121 to the junction point 122. Thereafter the grounded negative is traceable over line 123, contact pair 125 of relay 45 which is now closed due to the de-energization of relay 45, line 126 to the three upper contacts of the afore-described contact pairs 49, 51, and 52.

Thereafter upon the energization of any of 30 these three contact pairs, ground may be extended over lines 127, 128, or 129, respectively, 40 of the contact tongue 131, 132, or 133 of the shunt selector relay BL, LS, or ISP. In accordance with the instant example the first character of the identification signal being space, there will be operated accordingly the SP relay, Fig. 3, over the following circuit. As a result of the energization of the SP selector bar, Fig. 2, the contact pair 51 will be closed and negative potential from line 126 will be extended over the branch conductor 128 traversing the contact pair 132 of 45 relay LS which is closed because of the de-energization of this relay, then over line 134 through the contact pair 135 of relay BL which is also de-energized at this time, then over line 136 through the winding of the space relay SP, line 137 to the positive bus wire 138 which connects with plus battery at 83.

As a result of the energization of relay SP 50 there will be drawn up its several armatures 139, 141, 133, 76, 77, 78, and 79. As a result of the drawing up of armature 139, relay SP is no longer dependent upon minus current incoming through line 136 but may instead obtain minus current over a circuit which continues over line 142 through the now closed contact pair 143 of a make-before-break contact set under the control of relay SP-LS, then over line 144 through the now closed contact pair 145 of the make-before-break contact set of relay BL-SP, thence over line 146 to the now closed contact pair 147 of the 60 make-before-break contact set under the supervision of relay LS-BL, thence over line 148 to the now closed contact pair 149 of a make-before-break contact set under the supervision of relay LS-SP.

70 Thereafter the circuit is traceable over line 151

to the normally closed contact pair 152 of a make-before-break contact set under the supervision of relay BL-LS, thence over line 153 to the normally closed contact pair 154 of a make-before-break contact set under the supervision of relay SP-BL. Thereafter, the circuit is traceable over line 155 to the junction point 156, Fig. 2, branch conductor 157 to the contact armature 113 which is now closed due to the energization of relay 46, thence over line 158, to the junction point 159. Thereafter the circuit continues over a line 161 to the minus bus bar 91.

Accordingly, the continued energization of relay SP of the shunt selector group of Fig. 3 will prevail so long as relay 46 continues to be energized. Under the example chosen the first selecting signal SP is followed by another index signal BL causing to be operated the blank selector bar BL of the mechanical selector 42, Fig. 2. In consequence the contact pair 52 is closed extending ground from the afore-described supply line 126 on to the further conductor 129, which connects with the contact armature 133 of relay SP now attracted and in engagement with its front contact point 162. This extends ground over the branch conductor 163 through the winding of relay SP-BL over line 164 to the positive bus wire 138 causing said relay SP-BL to become energized.

As a consequence of the energization of relay SP-BL it draws up its armatures 165, 76, 77, 78, and 79. As a result of the operation of armature 165 the make-before-break contact assembly of relay SP-BL is operated so as to separate the contact pair 154 which had been in the locking circuit of relay SP and holding the afore-described shunt selector relay energized. Thus the energization of the relay SP-BL releases the previously energized relay SP and since the connector straps 81 of relay SP-BL are so arranged that its armatures 77 and 79 connect the common bus 82 over lines 74 and 75 thereby differing from its armatures 76 and 78, a condition obtains whereat reperforator shunt relays 58 and 61 will subsequently be effective to the exclusion of relays 57 and 59.

As a consequence signals incoming over the local loop circuit 19 will be effective to operate reperforators 27 and 29 but not reperforators 28 and 31. In this way signals will be issued over lines 36, and 38, but not lines 37 and 39.

Following the transmission of the second identification signal blank as afore-described thereby completing the transmission of the station identification signals constituted of space and blanks and recordable by the energization of relay SP-BL, it is contemplated that in accordance with the practice the station will transmit another carriage return signal causing to be operated the CR selector of the mechanical selector unit 42, Fig. 2. There is effected thereby a closure of the contact pair 48 which operates to short circuit the winding of the third conditioning relay 47 momentarily beginning with minus battery conductor 91 and traceable over the contact pair 53 through the closed contactors 55 and 54 of branch circuit 56, then over line 119 through the contactor 116 of the second conditioning relay 46 which is at this time energized, over line 121 to the junction point 122, then over branch conductor 166, contactor 92, to the left terminal winding of relay 47, the right terminal being normally minus. As soon as the universal contactor 54 is opened, however, which function

occurs after but a brief interval of closure due to the characteristic operation of the universal bar in the mechanical selector apparatus, the afore-described shorting circuit is broken and immediately operating current is made available to relay 47 over the following course.

Beginning with positive at battery terminal 83 this circuit is traceable over conductors 84 and 85 through the winding of relay 47 then out over conductor 86, through the contact tongue 115 and its contactor with which it is at the time engaged due to the energization of the second conditioning relay 46, then out over line 167 to the contact tongue 168 of relay 45 which is now closed, thence over conductors 169 and 108 to the junction point 109. Thereafter the course is traceable over branch conductor 171 through the contactor 53 which is closed to minus battery bus 91.

20 This causes relay 47 to attract again its armatures 92, 93, 94, and 95 providing an alternative source of negative current through armature 95 so that the energization of relay 47 is no longer dependent upon the continued closure of contact pair 53. The alternative negative potential supply source is traceable at junction point 109 over line 111 through the contact pair 95 to the minus bus wire 91.

25 This same alternative connection to minus current also supplies a holding circuit for relay 46 whose minus terminal extends over line 103, through the contact pair 114, line 118, through the contact pair 95 of relay 47, and then to negative bus 91. The same contact tongue 95 of relay 47 also provides an alternative negative source connection over the following course, from the minus terminal of relay 45 through common contact point 173 of the make-before-break contact switch of relay 45, its armature 174, lines 175 and 108, to the junction point 109, then over line 111 to the contact pair 95 of relay 47, to ground minus bus wire 91.

30 At the conclusion of the second carriage return signal, therefore, relays 45, 46, and 47 are all energized and so held over self-locking circuits in readiness for the transmission of a message to those of the retransmitting perforator stations 27, 28, 29, and 31, that have been selectively conditioned due to the corresponding operation of the 35 reperforator shunt relays 57 to 61. This was obtained by the energization of one of the selecting shunt relays of Fig. 3, in the particular instance, the relay designated SP-BL.

35 As has already been explained, each relay of this group is not necessarily committed to any particular arrangement of conditioning the reperforators 27 to 31 because any one of these relays SP, BL, etc., may, if desired, be variously connected by the operation of the straps or connector switches 81 so as to render it responsive to select any one or ones of the reperforators under the control of the particular identification signals space, blank, letters shift, etc. as may be desired.

40 If the message which is thereafter transmitted by any one of the outlying stations 15, 16, or 17, does not exceed in length the width of the page on the printer 41, there will be transmitted at the conclusion thereof, as is the practice under conventional page printer operation, a carriage return signal followed by a line feed signal. In page printer mechanisms of this class, these signals serve to restore the carriage to the start of line position and to rotate the platen throughout an angular distance to present a subsequent line for

printing. There will be described hereinafter the operation of apparatus which responds to these two signals in a manner which will restore the conditioning relays 45 to 47 and through them the shunt selecting relays, Fig. 3, to their normal condition to await a subsequent message and station identification signals.

If, however, the message which is transmitted by any one of the stations 15, 16, or 17 exceeds in line length the width of a page, then means are provided whereby through the transmission of the carriage return signal followed by the letters shift signal, before the line feed signal, there is effected a suspension of the wipe out or clear out operation causing instead the performance of the mechanical carriage return and line feed functions for the purpose of conventional printer control, while yet maintaining circuit connections with the destination station 27 to 31 as established by the previous line of transmission. Moreover, this arrangement may be perpetuated so long as any one of the lines is terminated by the transmission of the three instead of the two concluding signals as afore-described.

The transmission of the concluding carriage return signal has the effect of short circuiting the second conditioning relay 46. It will be recalled that positive battery source is available to relay 46 from positive battery terminal 83, over line 84, resistance 176, line 117 to contact armature 112, then through contact 102 to one of the terminals of the winding of relay 46. Upon the closure of contact pair 48, however, grounded battery is extended to this side of the relay thereby neutralizing the effect of its holding current through a circuit traceable as follows. Beginning with minus bus 91, through the contact pair 53, contacts 55 and 54 of branch conductor 56, through the contact pair 48, line 89, line 177 to the contact pair 178 of conditioning relay 45, now closed, then over line 179 to the contact pair 94 of relay 47, to the branch positive current conductor 117 at junction point 181.

This places minus battery at both ends of the relay 46 causing said relay to become de-energized and thereby release its locking circuit. It will be recalled that the locking circuit for relay 47 was traced through make-before-break contact set 115 of relay 46, and that as a consequence of the de-energization of relay 46, connection is broken between its armature 120 and the intermediate contact 182. Before the disconnection, however, contact 182 makes engagements with its alternative contact point 183. This circuit, including contact point 183, leads to the contact pair 48 of the carriage return pull bar and accordingly, the holding of relay 47 in its operated position will then prevail so long as the contact pair 48 remains closed over a path traceable from minus bus 91, through the contact pair 53, contact pairs 55 and 54 of branch conductor 56, through the contact pair 48, line 89, to the junction point 184, then through the contact pair 185, now closed, due to the energization of relay 45, over line 186, through the contact pairs 183-182 over line 86, to the winding of relay 47, then out over lines 85 and 84 to the positive battery terminal 83.

After a brief interval, contact pair 48 opens, breaking the holding circuit for relay 47 whereupon both of the relays 46 and 47 become de-energized leaving only the conditioning relay 45 energized. At this time the holding circuit for relay 45 is traceable from the minus bar 91 through the contact pair 53, then over line 171 to

junction 109, line 108 to the junction point 187, then over line 175, contactors 174 and 173, through the winding of relay 45 then out over line 188, line 84 to positive battery terminal 83. Thus relay 45 depends upon the continued closure of contact pair 53 for retaining itself in locked condition.

Negative potential is meanwhile supplied to the line 155 of the shunt selector relay group, 10 Fig. 3, over a course traceable from minus conductor 91 over line 161 to the junction 159, then over line 189, through the contact pair 191 of relay 45, line 192 to the line 155, through the contactor 165, winding of relay SP-BL, then out 15 over line 64 to the positive bus wire 138. This maintains relay SP-BL energized during the time that relay 45 remains locked.

Negative potential is also provided to the minus branch bus 82 during the energization of relay 20 45 over a course traceable from minus conductor 91 through the line feed contact pair 53, over conductor 171, to the junction 109, then over lines 108 and 175, through the contact pair 174-173 to the common negative bus branch 82. This source of negative potential is also dependent upon for the continued energization of relay 45.

At this time if a line feed signal were to be sent actuating the line feed pull bar LF, the contact pair 53 would be opened removing minus 30 current potential from a circuit which had been holding relay 45 locked and thereby permitting said relay to become de-energized releasing also the afore-described available ground connections to lines 82 and 155. However, if the message 35 under transmission is one which requires more than a single page printer line for its recording, a line feed signal must not immediately follow the transmission of the last described carriage return signal but instead a letters shift combination signal should intervene, causing to be closed the contact pair 49 for establishing a circuit to re-energize the second conditioning relay 46 as follows.

The new energizing circuit for relay 46 is traceable from positive battery terminal 83, over line 45 84, resistance 176, lines 117 and 193, through the contact pair 194, now closed due to the energization of relay 45, line 196, through the winding of relay 46, then out over line 103, through the contact pair 104 now closed due to the de-energization of relay 46, line 105, contactor 197 now closed due to the energization of relay 45, line 198 to the junction point 199, then over line 119, circuit 50 56 including its contact pairs 54 and 55, through the contact pair 53, to minus bus terminal 91.

Accordingly, relay 46 becomes energized pulling up its several armatures as afore-described and establishing a locking circuit for itself traceable from positive battery terminal 83, over line 84, 60 through resistance 176, line 117, to the junction point 181, then through contactors 112 and 102 through the winding of relay 46, over line 103, through the contact pair 114, now closed, lines 118 and 111 to the junction point 109. This circuit is further traceable over line 171 through the contact pair 53 to the minus bus wire 91. The operation of the mechanical selector's contact pair LS has no effect upon the shunt selector relays, Fig. 3, because at this time, due to the 65 energized condition of the first conditioning relay 45, contact pair 125 is open and thereat prevents the extension of positive current source to the common line wire 126.

With the operation of the conditioning relay 70 46, whose contact pair 114 is adjusted so as to

close an instant before the contact pair 104 is permitted to open, a locking current is established over line 103 which had extended through the contact pair 104 and is now extended through the contact pair 114, line 118, line 111 to the junction point 109, then over line 171 to the junction point 53 and minus bus 91. As was the case during the previously described operation, momentary closure of contact pair 54 as the result of the operation of the universal bar in the mechanical selector apparatus, prevented the immediate energization of relay 47 as a result of the energization of relay 46 which otherwise would proceed over the course beginning with the minus bus 91 through the contact pair 53, line 171 to the junction 109, then over lines 108 and 169 to the contact pair 168, line 167 through the contact pair 115—182 then over line 86 through the winding of relay 47, line 85 to positive battery terminal 83.

Thus, the closure of contact pair 92, due to the de-energizing condition of relay 47 and the operation of the universal contact pair 54 of the mechanical selector, momentarily prevents the energization of relay 47 by applying minus battery potential at the line 85 terminal of the relay 47 winding tractable from minus bus 91, through the line feed contact pair 53, then through contact pairs 55 and 54 of conductor 56, over conductor 119 through the contact tongue 116 and its contact point of relay 46 which is then energized, over lines 121, junction 122, then over line 166 to the contact pair 92 of relay 47, applying negative potential at junction 209 of line 85 which connects with the positive battery terminal through a suitable resistance.

After the completion of the selection cycle by the mechanical selector apparatus, contact pair 54 is opened whereupon the short circuiting of relay 47 is terminated and said relay is permitted to become energized in accordance with the previously described energizing circuit. As before, the operation of relay 47 attracts its several armatures 92, 93, 94, and 95. As a result of the closure of contact armature 95, negative potential over an alternative course is provided making unnecessary the continuous closure of contact 53. This provides an alternative connection for the negative potential of the locking circuits of the relays 45, 46, and 47, after the manner already described so that upon the operation of the line feed contacts 53 in response to the conventional line feed end-of-line signal, the opening of contact pair 53 will not interrupt the established connection between the incoming transmitters 15, 16, 17, etc., and the particular ones of the reperforators 27, 28, etc., but will merely function idly so far as the station selection apparatus is concerned, permitting the succeeding line to be printed under the same conditions of line connection as prevailed for the preceding line.

There will now be described another example of station selection in accordance with which an identification signal of but a single signal component will be employed such as the spacing signal. The spacing relay SP, Fig. 3, will be noted to have three of its straps 81, connected with the line 82. A different selective condition will now obtain because its contactors 77, 78, and 79 alone are thereby conditioned whereas its contactor 76 is disconnected at strap switch 81. Accordingly, upon the energization of relay SP, selective communication will prevail for reperforator shunt relays 58, 59, and 61 but not for relay 57.

As with the case of the preceding selection, the outlying station 15, 16, or 17 will transmit a carriage return signal effecting the closure of contact pair 48 and extending negative potential from bus wire 91 through the contact pairs 53, 55, and 54 over line 89. It will be recalled that at the start of each selection none of the relays 45, 46, or 47 is energized and that because the extension of negative potential over line 82 requires the energization of relay 45, any of the previously operated ones of the shunt selecting relays, Fig. 3, has been released. From line 89 the afore-described circuit is traceable over contact pair 87—88, now closed due to the de-energization of relay 46, then over line 86 to the winding of relay 47, then over line 85, through a resistance and positive bus terminal 83, thereby causing relay 47 to become energized. As a result of energization of relay 47 it attracts its armatures 92, 93, 94, and 95 establishing for itself a locking circuit over armature 93 as already described above. The winding of relay 46 lies in the locking circuit for relay 47 so that accordingly, due to the attraction of armature 93, an energizing circuit for relay 46 is thereby established as a result of which its several armatures 112, 104, 113, etc., are drawn up. Relay 46 establishes for itself a locking circuit through the operation of armature 112 in supplying a new source of positive current over line 117, meanwhile supplementing the existing source over line 99 through the operation of its make-before-break contact set 101—102.

The separation of the contact pair 101—102 opens the locking circuit for relay 47 whereupon the latter is released and a condition obtains in which relay 46 of the group of the conditioning relay set is the sole one to be energized. The conditioning relay set is now in readiness for the receipt of one or more of the special selecting signals for operating the identification signal contact pairs 49, 51, or 52. Under the supposed example, there will now be transmitted a single selecting signal by one of the outlying stations 15, 16, 17, etc., such as the spacing signal which will cause the closure of contact pair 51. As a result, minus potential, which had been available as far as the branch conductor 126, is now extended over conductor 128 through the contact pair 132 of relay LS then over line 134 to the contact pair 135 of relay BL, line 136 through the winding of space relay SP to the common positive bus line 137, causing to be energized the relay SP, and drawing up its several armatures 139, 141, 133, 76, 77, 78, and 79. Accordingly, there will be brought into operation the reperforator shunt relays 58, 59, and 61 to the exclusion of the relay 57.

In a similar manner, through the operation of any one of the relays SP, BL, LS, SP—LS, etc., there may be obtained a responsive selection to any signal combination of the three components LS, SP, and BL due to the operation of their corresponding selector bars in the mechanical selector, which in turn are controlled by the function signals transmitted by stations 15, 16, 17, etc.

While the present invention has been explained and described with reference to a particularly contemplated circuit arrangement, it is to be understood, nevertheless, that numerous modifications and variations may be made without departing from the essential spirit or scope thereof. Accordingly, it is not intended that any of the foregoing detailed description nor

that the specific illustrations in the accompanying drawings shall constitute the limitations upon its spirit or scope except as defined by the hereunto appended claims.

What is claimed is:

1. In a broadcast system, a central station, an incoming line for said station including a plurality of bulletin transmitters, a plurality of retransmitters at said central station, means responsive to bulletin messages preceded by identification signals for conditioning predetermined ones of said retransmitters according to chosen arrangement, means responsive to a concluding signal of each bulletin message for restoring to normal said conditioned ones of said retransmitters, and further means responsive to a preventing signal preceding said concluding signal for prolonging the condition of said ones of said retransmitters.

2. In a page printer transmission system, apparatus for sending an end-of-line signal for restoring page printers to beginning of line position, line switching control apparatus also responsive to said end-of-line signal, and electromagnetic means conditioned by a special control signal preceding said end-of-line signal for nullifying its line switching control.

3. In an automatic exchange system, an incoming line, a plurality of outgoing lines, a plurality of transmitting stations serially connected over said incoming line having means for sending bulletin messages comprising initial identification signals and concluding signals, a plurality of retransmission apparatuses including perforating devices for issuing signals over related ones of said plurality of outgoing lines, means responsive to said bulletin message initial identification signals for establishing communication between said incoming line and predetermined ones of said reperforating devices, means responsive to said concluding signals for releasing from communication with said incoming lines those of said reperforating devices with which communication was established by the initial signals of a related message, and relay means under the control of a special signal preceding said concluding signal for rendering said communication releasing means nonresponsive to said concluding signal.

4. In a system for automatically connecting 50

one or more of a plurality of outgoing lines with a common incoming line, a selector mechanism comprising a plurality of individually selectable elements responsive to telegraph printer function signals exclusive of character printing signals, a system of relays responsive to any one or more function signals for establishing communication between said incoming line and certain one or more of said outgoing lines in accordance with the particular nature of the signals, means responsive to an end-of-line signal for disconnecting said outgoing lines from communication with said incoming line, and apparatus under the control of a preconditioning signal immediately preceding said end-of-line signal for disabling said disconnecting means.

5. In a telegraph signaling system, an automatic station selecting apparatus comprising means responsive to combinations of certain permutation code signals for establishing communication between an incoming line and certain ones of a series of branch circuits according to the particular signal combination, apparatus responsive to certain periodic function signals for disconnecting said incoming line from said branch circuits, and means responsive to a disabling signal for preventing said apparatus from responding to its said disconnect signal.

6. The combination set forth in claim 5 in which said disconnection is achieved in response to a line feed signal terminating the transmission of each page printer line width of communication, and in which said disabling signal is a case shift controlling signal.

7. In a telegraph communication system, a station selecting apparatus responsive automatically to signals preceding a message line, comprising electromagnetic means selectable by certain printing function signals for establishing a line switching connection between an incoming line and corresponding ones of a class of branch circuits, apparatus responsive to end-of-line printing function control signals for breaking said connection between said incoming line and said ones of said circuits, and means responsive to a disconnect preventing signal for immunizing said apparatus from responding to its said disconnect signal.

ARTHUR J. DORÉ.
